UNITED STATES PATENT OFFICE.

GROVER C. ROYSE, OF TACOMA, WASHINGTON.

REINFORCING ELEMENT FOR CONCRETE.

1,317,824.

Specification of Letters Patent.

Patented Oct. 7, 1919.

Application filed May 17, 1916. Serial No. 98,093.

To all whom it may concern:

Be it known that I, GROVER C. ROYSE, a citizen of the United States, residing at Tacoma, in the county of Pierce, State of Washington, have invented certain new and useful Improvements in Reinforcing Elements for Concrete; and I do hereby declare the following to be a full, clear, and exact description of the invention, such as will 10 enable others skilled in the art to which it appertains to make and use the same.

My invention relates to reinforcing elements for concrete construction, and has particular reference to reinforcing bars for 15 use in any loose rod system of concrete reinforcement.

The primary object of my invention is to provide a reinforcing bar for concrete construction which will possess a maximum 20 of reinforcing efficiency, both from the standpoints of bonding effect and tensile strength, with a minimum of required weight of metal.

It is furthermore an object of the invention to provide a reinforcing element of the deformed bar type, which can be constructed with a minimum of labor, and in which a large part of the tensile strength is due to the working of the metal by the rolls, and 25 in which the deformations are so constructed and arranged that the bar may be used in any class of work where the loose rod system is used without special positioning of the rods or bars with regard to the deformations.

In the various forms of deformed reinforcing bars, which are known to me, certain disadvantages to the practical universal use of the bars are apparent. Either 30 the amount of metal which is necessary to the requisite strength of the bar, or for the formation of the deformities, makes the cost of the bars prohibitive, or else, the bars do not combine the requisite properties of 35 bond and tensile strength, due to some lack of proper proportion. For these and other reasons, the square twisted bar has been found to be the most practical of all deformed bars to my knowledge.

However, the twisted bar above mentioned 40 also possesses certain disadvantages, the principal one arising from the fact that there is always a tendency, where the bar is gripped at one end, for it to twist or turn and 45 therefore cause the concrete to crack.

It is one of the principal objects of my in-

vention to avoid such a twisting tendency by certain of the peculiarities of construction embodied in my invention. It might be mentioned that the square twisted bar 50 requires a rehandling in its manufacture to provide the twist, an item which does not appear in the manufacture of the bar of my invention.

In providing a deformed bar in which the bond and tensile strength are properly proportioned, I have, as another object of my invention, to provide a construction in which the bar possesses a constant sectional area, the provision of such a constant sectional 55 area arising from the suitable and peculiar disposition of lugs or webs, which extend in directions to brace the body of the bar from all angles, so that, in effect, the body becomes practically a trussed bar.

The peculiar arrangement of lugs or webs above mentioned also affords a great resistance to the bending of the bar, even when the latter is not used as a reinforcing element, and furthermore permits the construction 60 of a bar which requires a relatively small amount of space in a concrete mass when considered in connection with the bonding properties of the bar.

It is to be noted, in connection with the following description, that my improved bar may be constructed for use in any kind of reinforcing concrete construction without requiring the use of any greater number of sizes than is required of the plain bars now 65 in ordinary use.

With the above, and other objects in view, as will hereinafter appear, my invention will now be fully set forth and described, reference being had to the accompanying drawings.

In said drawings, Figure 1, for the sake of clearness is called a front elevation of a section of a bar forming the subject matter of my invention,

Fig. 2 is a rear elevation,

Fig. 3 is a plan view,

Fig. 4 is a bottom view of the bar as the latter is viewed when held in the same position as Fig. 1,

Fig. 5 is an elevation of the bar when the latter has been turned on its axis to another position,

Fig. 6 is a rear elevation,

Fig. 7 is a bottom view,

Fig. 8 is a plan view of the bar when held in the same position as Fig. 5,

Fig. 9 is a section on line 9—9 of Fig. 2,
Fig. 10 is a section on line 10—10 of Fig. 3,
Fig. 11 is a perspective view of the bar,
and

5 Figs. 12 and 13 are cross sectional views
of the modifications of the construction illus-
trated in the foregoing figures.

Referring more particularly to said draw-
ings, *a* represents the body of the bar, which
10 is provided with a plurality of longitudinal
wings or ribs *b*. In Figs. 1 to 11, the body
a is shown provided with four equally spaced
ribs *b*, and in the modified forms of Figs. 12
and 13 respectively, the body is shown pro-
15 vided with two wings and three wings.

In the preferred form of Figs. 1 to 11, the
ribs or wings *b* project at equal distances
apart from the body *a*, and are widened at
their bases so that they merge into the body
20 portion *a* of the bar.

Disposed between the wings or ribs *b*, and
rising from the body *a*, are sets of webs or
lugs, said lugs being arranged, practically,
in two groups, the lugs *c* and *d* appearing
25 on opposite sides of the wing or rib *b* in Fig.
1 representing one group and the lugs or
webs *e* and *f*, rising on opposite sides of the
rib *b* in Fig. 2 constituting the second group.
It will be noted that the group *c*, *d* appears
30 on the opposite side of the bar from the
group *e*, *f*.

The extreme outline of the bar, in cross
section, as best seen in Figs. 9, 10, 12 and
35 13 is circular, since the webs or lugs *c*, *d*, *e*
and *f* have their free edges rounded and
their extremities so merged into the ribs *b*
that the bar, in effect, is circular in cross
section.

As noted in Fig. 1, the lugs or webs *c* and
40 *d* form substantially a continuous web
through the rib *b*, all of said continuous
webs thus formed extending diagonally in
one direction and in parallelism, and the
lugs being spaced apart longitudinally a
45 distance equal to the greater diameter of
the rod.

As shown in Fig. 2, the group of lugs *e*
and *f* which appear upon the opposite side
50 of the bar also constitute substantial con-
tinuous webs extending through the oppo-
site corresponding rib *b*, the continuous webs
on this side also extending in substantial
diagonal parallelism, but in the opposite
diagonal direction from that in which the
55 group *c*, *d* is positioned.

As hereinabove mentioned, it is a primary
object of my invention to provide a reinforcing
bar of constant cross sectional area, and
the disposition of the lugs *c*, *d*, *e* and *f*, and
60 the groups of lugs *c*, *d*, and *e*, *f* possess a
function to this end.

As above described, the lugs on one side
of the bar, as illustrated in Fig. 1, run in
one direction, while those on the opposite
65 side of the bar run in the opposite diagonal

direction, and furthermore, the lugs on both
sides, which form the two groups referred
to, meet in a common point, and appear to
form a continuous ridge through the rib on
the corresponding part of the bar.

70

Referring now to Figs. 3 and 4, it will be
noted that the webs *c* and the webs *e* which
appear in the front elevation of the bar
range in opposite directions from the side
rib *b* which appears in this elevation, and
75 that the webs or wings *d* and *f* which appear
on the opposite side or rear elevation of the
bar also range in opposite directions from
the corresponding side rib, but that they also
extend in the opposite direction from the
80 webs *c* and *e* which appear in the front elevation.

The group *c*, *d* of webs, which appears
upon the upper side of the bar, is staggered
or shifted lengthwise of the bar one-quarter
of the diameter of the latter, with reference
85 to the group *e* and *f* which appears upon
the lower side of the bar. This staggered
relation of the groups is illustrated in Figs.
3 and 4, where it will be noted that the webs
90 *c* and *d* do not converge to a common point
upon the corresponding ribs *b* with the webs
or lugs *e* and *f*.

The above combination and arrangement
of ribs and lugs provides the constant cross
95 sectional area of the bar.

Fig. 9 is a cross section through the bar
at one point, and shows, aside from the sym-
metrical arrangement of ribs *b* and the cir-
cular contour of the webs *c*, *d*, *e* and *f*, an
100 offset or projection *f'*, which is a section
through the middle point of one of the
webs *f*.

Fig. 10 is a section through the bar at a
different point, so that the intersecting
105 plane, instead of cutting merely one of the
webs or lugs, intersects two of the lugs, as
e, *d*, so that projections *e'* and *d'* are formed,
but it will be noted that the area of the pro-
jection *f'* in Fig. 9 is equal to the combined
110 areas of projections *e'* and *d'* in Fig. 10.
Therefore, since the cross sectional area of
the rod *a* is constant throughout the latter,
this area added to the sectional areas of the
lug or lugs *c*, *d*, *e* or *f* which occurs at any
115 particular point along the bar is a uniform
quantity.

Figs. 5, 6, 7 and 8 are views taken with
the short diameter of the rod in elevation.
in this position, the lugs or webs *c*, *d*, *e* and
120 *f* appearing to project above the body of
the bar. The directions in which the various
lugs extend, and the relationship of adjacent
groups and series of lugs are clearly dis-
closed.

125 The channels formed between the ribs *b*
are spanned by the webs or lugs which ex-
tend in one diagonal direction in one chan-
nel and in an opposite diagonal direction in
an adjacent channel, when viewed in the
130

light of the last mentioned figures, and serving not only to provide an increased bond, but act to greatly increase the strength of the bar, so that all surplus weight of 5 metal in the bar is avoided, and all of the metal in the bar is employed to resist any tensional strain on the latter. In such deformed bars with which I am familiar, the sole function of lugs is to provide greater 10 bond, and any metal used in this manner is a surplus, and the engineer is required to select bars of sufficient sectional area, aside from the area of the lugs, to resist the tension to which the bars would be subjected. 15 Since steel is sold by weight, it will be readily recognized that the saving of weight which is accounted for by my improved construction will constitute a considerable item in making estimates for any particular piece 20 of work.

By reason of the circular contour which is provided by the arrangement of ribs and lugs, my improved bar construction provides, with a minimum of metal or weight of 25 metal, a maximum shear area, and it will be furthermore noted, that whatever appearance one side of my bar presents, the opposite side will present an identical but opposite arrangement of parts, so that when the 30 bar has been embedded in a piece of concrete, there is no tendency for the bar to break out of the concrete by reason of horizontal, vertical or turning action. Any stress coming on the lugs on one or more 35 sides of the bar that would tend to turn or move it in any direction is counteracted by an equal force of stress upon the lugs on the opposite side. Furthermore, all sharp edges or corners which are common in twisted bars 40 are avoided in the present construction, so that the tendency of concrete to crack along such sharp edges is avoided. By reason of the construction above defined, I have found my reinforcing bar to be valuable in reinforcing the undersides of concrete floor slabs 45 or girders, since the lugs run at such an angle that even where concrete has been loosened by the heat of a fire, a comparatively small part of the concrete will fall 50 away from the bars because the lugs and ribs provide a firm lock for the concrete.

It has been stated that my improved bar is intended to possess a maximum of tensile strength with a minimum of metal, and this 55 is accomplished also by the particular arrangement of the lugs between the ribs, so that, no matter what position the bar may assume in a concrete construction, proper provision is made for bracing the bar against 60 bending in any of the four directions between the four points of ribs b of the bar, since the lugs not only span the ribs and merge with the body a , but also arch outwardly to provide a circular contour. In 65 this sense, the bar is reinforced or strength-

ened much in the same manner that a trussed girder is strengthened.

What is claimed is:—

1. A metallic bar for use as reinforcement in concrete construction having a uniform body portion longitudinally of the neutral axis, which body portion in cross section is formed with concave faces and the metal between the marginal portions of said faces forms radial ribs extending parallel with 70 but remote from the neutral axis to increase resistance to collapse by bending for any given weight of metal, and a plurality of isolated lugs extending diagonally across the concave faces from rib to rib, said lugs overlapping each other longitudinally of the bar and being of a cross sectional area which varies inversely throughout the overlapping portions whereby a uniform distribution of metal in the lugs is effected throughout the 75 length of the bar and the combined cross sectional area of the body and lugs is substantially a constant.

2. A metallic bar for use as reinforcement in concrete construction having a uniform 80 body portion longitudinally of the neutral axis, which body portion in cross section is formed with equally spaced concave faces and the metal between the marginal portions of said faces forms equally spaced radial 85 ribs extending parallel with but remote from the neutral axis to increase resistance to collapse by bending for any given weight of metal and a plurality of isolated lugs extending diagonally across the respective concave faces and at their ends merging into the edges of the ribs, said lugs overlapping each 90 other longitudinally of the bar and being of a cross sectional area which varies inversely 95 throughout the overlapping portions whereby a uniform distribution of metal in the lugs is effected throughout the length of the bar and the combined cross sectional area of the body and lugs is substantially a constant.

3. A metallic bar for use as reinforcement 100 in concrete construction having a body portion which in cross section is formed with diametrically opposite concave faces and the metal between the marginal portions of said faces forming longitudinal ribs remote from 105 and radial with respect to the neutral axis to increase resistance to collapse by bending for any given weight of metal and lugs integral with said body extending across the concavities from rib to rib, the lugs on diametrically opposite faces being arranged in 110 parallel planes inclined to the axis of the bar and the lugs being overlapped longitudinally of the bar and inversely varied in cross sectional area to effect a uniform distribution of metal and form a bar of substantially constant cross sectional area.

4. A metallic bar for use as reinforcement 115 in concrete structures having a body portion which is formed with two pairs of concave 120

- faces with the faces of each pair diametrically opposed and the metal between the marginal portions of said faces forming longitudinal ribs remote from the neutral axis
- 5 to increase resistance to collapse by bending for any given weight of metal and lugs integral with said body extending across the concavities from rib to rib, the lugs on diametrically opposite faces being arranged in
- 10 parallel planes inclined to the axis of the bar, the planes of inclination of the lugs on one pair of faces intersecting the planes of inclination of the lugs on the other pair of faces, said lugs being overlapped longitudinally of the bar and varied inversely in cross sectional area to effect a uniform distribution of metal and form a bar of substantially constant cross sectional area.
5. A metal bar for reinforcement in concrete construction polygonal in cross section, 20 each face being concave transversely of the bar and a series of lugs extending across the concavities in planes inclined to the neutral axis of the bar, said lugs overlapping each other to maintain the constant section of 25 the bar and having their outer edges curved in arcs having the neutral axis of the bar as a center and their inner portions made to conform to the curve of the concave faces of the bar. 30

In testimony whereof I affix my signature in the presence of two witnesses.

GROVER C. ROYSE.
